THERAPEUTIC TABLE WITH ADJUSTABLE SECTION TOP

Kenneth G. Palmer, Chicago, Ill.

Application April 15, 1947, Serial No. 741,491

6 Claims. (Cl. 311—7)

1

This invention relates to tables having adjustable elements such as used in hospitals, doctors' offices, and the like, and in particular a hydraulic or pneumatically actuated treating and operating table upon which a patient may be placed for efficient examination, treatment, or operation.

The purpose of this invention is to provide a table having adjustable elements adapted for general use by physicians, practitioners, surgeons, osteopaths, chiropractors, naprapaths, naturopathic physicians, masseurs, physiotherapists, and particularly for colonic irrigations, wherein a section of the table upon which the patient is placed is raised and lowered by fluid-actuated cylinders and the main or stationary part of the table is provided with a plurality of fluid containers with mixing valves associated therewith, and a toilet or overflow bowl.

Various types of adjustable tables and also tables with adjustable elements have been provided for use in hospitals, doctors' offices, and the like, but in tables for general use, a patient is positioned upon the stationary frame or section of the table, and adjustable elements are provided for the arms, limbs and head. For some uses, however, it is desirable to position the patient on an adjustable section of an operating table with the physician located at a stationary section, wherein various accessories and equipment are provided on said stationary section. With this thought in mind, this invention contemplates a stationary section or frame providing a table with an extended patient-carrying section hinged to one end thereof and provided with compression cylinders for adjusting the elevation thereof, and also compression cylinders for actuating the inner end thereof.

The object of this invention is, therefore, to provide an operating table including a platform which may be bodily raised and lowered to the desired position of inclination with respect to the table frame and which may be bodily shifted inwardly and outwardly of the table frame.

Another object of the present invention is to provide an operating table including a platform which is movable by hydraulic means both vertically and horizontally.

Other features and advantages of the invention will appear from the following description taken in connection with the drawings, wherein:

Figure 1 is a plan view looking downward upon the upper surface of the table with parts broken away.

Figure 2 is a view showing a side elevation of the table also with parts broken away.

2

Figure 3 is a view showing an end elevation of the table looking toward the end of the stationary section thereof also with parts broken away.

Figure 4 is a view showing an end elevation of the platform illustrating one of the head rests thereof with parts omitted.

Figure 5 is a similar view illustrating a head rest of a different design and with the parts of the table omitted.

Figure 6 is a view showing an end elevation of the head rest shown in Figure 5.

Figure 7 is a view illustrating the upper leg support.

Figure 8 is a detail showing the paper roll holder.

Figure 9 is a fragmentary side elevational view showing one of the links and its connection to the platform and table frame, the full lines indicating the normal position of the link and platform and before the link has executed its arcuate movement, and the dotted lines indicating the position of the link and the platform after the link has executed its complete arcuate movement.

Figure 10 is a sectional view taken on the line 10—10 of Figure 9.

Referring now to the drawings, wherein like reference characters indicate corresponding parts, the main or stationary section 1 of the table is supported by legs 2 with upper tubular sections 3 at one end and legs 4 at the other, and the legs 2 and 4 are connected by cross-elements 5 with the legs 4 connected by a cross-bar 6. The upper section of the table frame is formed with a rectangularly-shaped frame having side members 7 and 8 with the ends connected by transverse members 9 and with the table top formed by a panel 10. The panel 10 extends continuously over the upper surface of the table and is provided with a circular opening 11 in which a conical-shaped bowl 12 is mounted and behind the bowl is an opening 13. The lower end of the bowl 12 is connected by a trap 14 to a drain 15, and the upper end is normally covered by a closure 16 hinged to the panel 10 by hinges 17 and 18.

A holder 19 for toilet paper and the like is provided in a panel 20 extending vertically upward at one side of the table, and a roll of paper 21 may be provided in the holder. The panel 20 is provided with a shelf 22 that may be used for holding instruments and accessories, and the panel is also provided with a socket 23 through which a flexible tube 24 with a light

socket 25 at the outer end, for holding a light bulb 26, may extend.

Light bulbs 27 may also be provided on the upper edge of a panel 28 at the end of the table, and these may be mounted in reflectors 29.

The panel 28 is provided with tanks 30, 31 and 32 which are positioned in openings in the panel with the surfaces of the tanks showing through the panel formed of transparent material 33, wherein the amount of the material in the tanks may readily be ascertained by the operator from the front of the table. The discharge connections from the tanks extend downward and under the table, and the connection from the tank 32 is provided with a two-way valve 34, whereas the connections from the tanks 30 and 31 are provided with three-way valves 35.

The table 1 is provided with straps 36 at the sides, and 37 at one end, by which patients may be held on the surface thereof, the straps 36 being slidably mounted on rods 38, and the straps 37 being held on hook-like elements 39.

The different solutions are supplied to the tanks through a mixing valve 40 which is provided with supply pipes 41 and 42, and the discharge from the mixing valve is connected to the tanks through pipe 43 with individual branches 44, 45 and 46. The mixing valve is controlled by a handle at the front of the panel, as indicated by the numeral 48, and the individual connections to the tanks are provided with valves 50. From the valves 34 and 35 the solutions of the tanks are supplied through valves 51 in the opening 13 of the panel 10 of the table through pipes 52, 54 and 56. A hinged cover 57 may be provided for covering the valves and closing the opening when the solutions are not used. From the valves 51 the connections are provided with flexible tubes 58 by which the solutions may be supplied at any point or points. The flexible connections or tubes 58 may have sufficient length to extend to the far end of the table, and may be used for colonic irrigation and the like.

The table is provided with an adjustable platform 59 having a panel 60 thereon, and the inner end of this platform is pivotally connected to the end of the stationary table 1 by connecting means or links 61 and 62 pivotally carried by the table 1. The outer portion of the platform 59 is supported through downwardly extending flanges 63 from diagonally extending tubular supports 64 through fluid-actuated cylinders which provide means for bodily raising and lowering the platform to the desired position of inclination with respect to the stationary frame 1. Water or other fluid is provided through tubes 65 in the supports from supply connections 66, the fluid being supplied through connections 67 and 68 to the cylinders 70, the lower ends of which are pivotally mounted in the members 64 through pins 71, and the upper ends of connecting rods 72 therein being connected to the flanges 63 by pins 73 through yokes 74. The under surface of the platform is provided with downwardly extending lugs 75 to which fluid cylinders 76 positioned on the under surface of the section are connected by connecting rods 77 with the opposite ends of the cylinders connected to the end of the table 1 by brackets 78. The cylinders 76 provide means for causing inward and outward movement of the platform 59 relative to the stationary table 1, the cylinders being connected at one end to a supply pipe 79 through which water or other fluid may be supplied under pressure.

The inner end of the platform 59 is provided with sockets 80 and 81 in which head and leg rests, as illustrated in Figures 5 and 7, may be held by lugs 82 and 83 extending downwardly from the head rest 84, and 85 and 86 extending downwardly from the leg rest 87. The end of the platform 59 is also provided with sockets 88 and 89 in which heel rests 90 may be held through adjustable arms 91 and 92, as shown in Figure 2. The head and leg rests may be provided with suitable cushioning material, as indicated by the dotted lines in Figure 4, as may be desired.

15 The outer end of the platform 59 is also provided with a head rest formed with vertically extending bars 93 and 94 with a horizontally disposed section 95 and with the lower ends of the bars clamped against the side members of the frame of the platform 59 by a rod 96 with a crank 97 on one end. The section 95 is covered with suitable upholstery, as indicated by the dotted lines.

15 The outer end of the platform 59 is also provided with a bracket 98 for supporting a roll 25 of paper 99 with the roll extending across the end of the platform, and with a bar 100 bearing against the paper roll, the bar 100 being carried by the outer ends of pivotally mounted arms 101 which are resiliently held by springs 102. 20 Paper from the roll may be drawn across the upper surface of the table to provide a clean surface for the patient. The ends of the bracket 98 are provided with small plates 103 to assist in holding the paper roll shaft to prevent endwise movement thereof. The sides of the platform 59 may also be provided with straps 36 and these may be mounted on brackets 104.

25 The platform 59 is provided with a slot or opening 105 to receive the face of a patient positioned face downward upon the table, and the upper surface of this section of the table is normally covered with 2-inch padding, as indicated by the dotted lines. The upper surface of the table 1 is normally provided with a 2-inch upholstered mattress 106 that is removed when the bowl is in use. The mattress is also indicated in dotted lines in Figure 2.

30 The table 10 is also provided with a water connection 107 having a valve 108 therein which is used for flushing the bowl 12. A connection having a valve 109 is in communication with supply pipe 66, the connection supplying water under pressure to supply line 66 which in turn supplies water through supply connections 67 and 68 to the cylinder 70 to actuate the connecting rods 72 movably mounted in the latter cylinders. 35 Actuation of the valve 109 to admit water into the cylinder 70 causes the connecting rods to bodily raise and lower the platform 59 to the desired position of inclination with respect to the stationary frame 1. A connection 110 having a valve 110 is in communication with the supply line 79, while a connection 110' connected to valve 110 is in communication with supply line 19' which is connected to the other end of the cylinder 76. The valves 51 in the opening 13 are secured to the under surface of the hinged cover plate 57, and as the cover is opened, the valves are drawn upward through the opening 13 for use.

40 It will also be noted that cushions may be provided on the various elements as may be desired, and in particular the head rest 84 illustrated in Figures 5 and 6 is provided with a cushion 111.

45 With the platform 59 hinged to the table frame

1 in this manner, the platform 59 may readily be bodily raised or lowered to the desired position of inclination relative to the stationary table 1 by actuation of the connecting rods 12 movably mounted in the cylinders 70, and the platform 59 then moved inward or outward with respect to the table frame 1 by actuation of the connecting rods 77 movably mounted in the cylinders 76, to accommodate the patient in the most comfortable or accommodating manner. The links 61 10 and 62 provide connecting means, and as noted, the inner ends of the links are connected to the main frame of the table 1 by pins 112, and the opposite ends are connected to the frame of the platform 59 by pins 113. Actuation of the valve 110 to admit water into said cylinders 76 so as to move the connecting rods 77 toward the stationary table frame 1 induces arcuate movement in one direction of the links 61 and 62, causing inward movement of the platform 59 relative to the table frame 1, the dotted line position of Figure 9, while actuation of the valve 110 to admit water into the cylinders 76 so as to move the connecting rods 77 away from the table frame 1, induces arcuate movement in the opposite direction on the links 61 and 62, causing outward movement of the platform 59 relative to the table frame 1, the full-line position of Figure 9. The table is provided with means which coact with the connecting means or links 61 and 62 to limit the arcuate movement in both directions of the links, and hence, the inward and outward movement of the platform 59 relative to the frame 1, said means, Figures 1, 9 and 10, comprising lugs 114 extending from the corners of the table frame and stops 115 extending from the sides of the table frame 1. The table is provided with extending lugs 114 on the corners of the frame and also stops 115 on the sides, wherein movement of the links 61 and 62 will be limited in both directions and with the adjoining end of the platform down, the links will be retained in substantially horizontal position.

With the parts arranged in this manner, the adjustable table of this invention is adapted for universal use, and for rectal or vaginal treatments, the head may now be placed upon the head rest 95 with the legs over the supports 87. In this position the feet may be held with the heels in the brackets 90. For some treatments, the patient may be placed upon the table with the face downward and the body may be held with the straps 36 with the feet secured by the straps 37. For other uses, the leg rests 87 may be removed and replaced by the head rest illustrated in Figure 5, wherein the head is positioned at the end of the table frame for examination and treatment. It will also be understood that the table may be used in combination with other equipment and other accessories or devices may be mounted thereon as may be desired.

I claim:

1. In an operating table, a stationary horizontally-disposed table frame, a horizontally-disposed platform arranged in end-to-end relation with respect to said table frame, connecting means extending between the meeting ends of said frame and platform and pivotally connected to each of the latter, fluid pressure means operatively connected to said platform for raising and lowering the latter bodily to the desired position of inclination with respect to said frame, and fluid pressure means operatively connected to said platform for causing inward and outward movement of the latter relative to said table frame.

2. In an operating table, a stationary horizontally-disposed table frame, a horizontally-disposed platform arranged in end-to-end relation with respect to said table frame, connecting means extending between the meeting ends of said frame and platform and pivotally connected to each of the latter, fluid pressure means operatively connected to said platform for raising and lowering the latter bodily to the desired position of inclination with respect to said frame, fluid pressure means operatively connected to said platform for causing inward and outward movement of the latter relative to said table frame, and means on said table frame and co-acting with 10 said connecting means for limiting the inward and outward movement of said platform relative to said table frame.

3. In an operating table, a stationary horizontally-disposed table frame, a horizontally-disposed platform arranged in end-to-end relation with respect to said table frame, connecting means embodying links extending between the meeting ends of said frame and platform and pivotally connected to each of the latter, fluid pressure means operatively connected to said platform for raising and lowering the latter bodily to the desired position of inclination with respect to said frame, fluid pressure means operatively connected to said platform for causing inward and outward movement of the latter relative to said table frame, and means embodying lugs extending from the corners and stops extending from the sides of the meeting end of said table frame and co-acting with said links for limiting 25 the inward and outward movement of said platform relative to said table frame.

4. In an operating table, a legged structure, a stationary horizontally-disposed table frame carried by said legged structure, a horizontally-disposed platform arranged in end-to-end relation with respect to said table frame, links extending between the meeting ends of said frame and platform and pivotally connected to each of the latter, fluid pressure means operatively connected to said platform for raising and lowering the latter bodily to the desired position of inclination with respect to said frame, said means including a pair of vertically-disposed cylinders 30 positioned under said platform and pivotally connected to said legged structure, a movably mounted connecting rod in each of said cylinders and having an end projecting therefrom, the projecting ends of said connecting rods being pivotally connected to said platform, and fluid pressure means operatively connected to said platform for causing inward and outward movement of the latter relative to said table frame.

5. In an operating table, a legged structure, a stationary horizontally-disposed table frame carried by said legged structure, a horizontally-disposed platform arranged in end-to-end relation with respect to said table frame, links extending between the meeting ends of said frame and platform and pivotally connected to each of the latter, fluid pressure means operatively connected to said platform for raising and lowering the latter bodily to the desired position of inclination with respect to said frame, said means including a pair of vertically-disposed cylinders positioned under said platform and pivotally connected to said legged structure, a movably-mounted connecting rod in each of said cylinders and having an end projecting therefrom, the projecting ends 35 of said connecting rods being pivotally connected

to said platform, and fluid pressure means operatively connected to said platform for causing inward and outward movement of the latter relative to said table frame, said last-named fluid-pressure means comprising a pair of horizontally-disposed cylinders arranged below and spaced from said platform and pivotally connected to said table frame, a movably-mounted connecting rod in each of said last-named cylinders and having an end projecting therefrom, the projecting end of each of the last-named connecting rods being pivotally connected to said table frame.

6. In an operating table, a legged structure, a stationary horizontally-disposed table frame carried by said legged structure, a horizontally-disposed platform arranged in end-to-end relation with respect to said table frame, links extending between the meeting ends of said frame and platform and pivotally connected to each of the latter, fluid pressure means operatively connected to said platform for raising and lowering the latter bodily to the desired position of inclination with respect to said frame, said means including a pair of vertically-disposed cylinders positioned under said platform and pivotally connected to said legged structure, a movably-mounted connecting rod in each of said cylinders and having an end projecting therefrom, the projecting ends of said connecting rods being pivotally connected to said platform, fluid pressure means operatively con-

10
